JAMES W. NELSON, OF NEW YORK, N. Y.

HYDRAULIC PRESSURE GENERATING AND APPLYING APPARATUS.

942,736.

Specification of Letters Patent. Patented Dec. 7, 1909.

Application filed February 20, 1908. Serial No. 416,842.

To all whom it may concern:

Be it known that I, JAMES W. NELSON, a citizen of the United States, and a resident of the city of New York, borough of Brooklyn, county of Kings, and State of New York, have invented certain new and useful Improvements in Hydraulic Pressure Generating and Applying Apparatus, of which the following is a specification.

10 This invention relates to apparatus for generating and applying hydraulic pressure, with more particular reference to exceedingly powerful jacks adapted to use in locations and under conditions which render 15 necessary or desirable the separation of the pressure generating means from the pressure applying means, with means located in close proximity to applying means for controlling both the generation and application 20 of pressure.

In a co-pending application, filed January 21, 1908, Ser. No. 412,026, I have shown and described a simpler form of apparatus of this character, in which a simple single-piston 25 ton pump is employed. In another copending application filed January 27, 1908, Ser. No. 412,855, I have shown and described a more powerful apparatus which includes two simple single-piston pumps, the controlling 30 means being adapted to render one of said pumps alone operative or both thereof, as desired. The present invention contemplates a still more powerful device in which three or more single-piston pumps 35 are employed, the pressure controlling means being common to all of said pumps and of such character that a single operator, stationed near the ram or rams, who is in position to note the progress and effect of the 40 work, may control and regulate the effect of the pumping operations.

The present invention may be said to reside in the provision of separate controlling means of the character above outlined common 45 to three or more individual pumping mechanisms which will automatically render effective the operation of one or more of said pumping mechanisms if individually operated, and which, if jointly operated, 50 either manually or mechanically or from a common source of power, may be manually controlled to render one or more of the pumps inoperative and finally relieve the pressure in the ram chamber or chambers.

55 My invention will be more readily understood by reference to the accompanying

drawings, forming a part of this specification, and in which—

Figure 1 is a diagrammatic view, with one of the rams in section, of a complete apparatus embodying my invention. Fig. 2 is an enlarged longitudinal section of the separate pressure controlling member; Fig. 3 is a reduced cross-section on the line 3 3 of Fig. 2; Fig. 4 is a similar section on the line 4 4 of Fig. 2; Fig. 5 is a reduced transverse section through the lower part of Fig. 2, and Fig. 6 is a view showing the manner of coupling the three pumps to a driving shaft and thus providing a common source 70 of power.

Referring now to the drawings in detail, numerals 11, 12 and 13 refer to three pumps which for the purposes of this description may be considered as being of the single-piston type and which may be of the same or different capacities. When they are the subjects of individual operation, as indicated in Fig. 1, the device may doubtless be given a wider range of usefulness by making these pumps of different capacities for operation in the manner which will be hereinafter set forth. In the construction and arrangement shown in Fig. 1, these pumps are provided with individual pumping levers 14, 15 and 16, respectively, and when jointly operated obviously require the attendance of three operators. When operated individually, it will be apparent that they may be located so close to each other 90 that a single operator may step from one to the other and selectively operate the particular pump of desired capacity. These pumps are without valves, each comprising a pump bore in which a piston is mounted 95 to reciprocate upon operation of the pump lever, and are each provided with a single duct leading from the bottom of the pump bore and at all times open through a suitable connection to a pipe which serves the 100 double function of supplying liquid to the pump chamber and transmitting the liquid under pressure generated by the pump. In the pump 11, the pipe 17 leads from the pump chamber, while the pipe 18 has a corresponding connection with the pump chamber in the pump 12 and the pipe 19 leads from the pump chamber in the pump 13.

All of the pump and pressure valves are located in a separate and individual member which comprises the preferably cylindrically-shaped body 20, suitably mounted

upon a heavy supporting standard 21 which serves to retain the body 20 at all times in a substantially vertical position. The lower end of the body 20 is bored to provide the 5 central chamber 22, the lower end of which, is closed and sealed by means of the screw- plug 23. In this bore or chamber 22 is mounted the push-tube 24, the lower end of which is provided with the in-turned flange 10 25 which provides a seat for the spring 26 in compression between said flange and the upper end of the bore 22 and tends to yieldingly force said tube 24 to its lowermost position. The flange 25 leaves a central aperture 27 permitting the flow of liquid to the 15 upper end of the bore or chamber 22.

The upper end of the member 20 is provided with the three similar and symmetrically located bores 28, 29 and 30, each of 20 which extends from the top of said body 20 to the larger bottom bore 22. As shown in Fig. 2, the top of the bore 28 is closed and sealed by means of the screw-plug 31 and the top of the bore 29 by means of the screw- 25 plug 32. The top of the bore 30 is closed in a similar manner by means of a precisely similar screw-plug which, to avoid confusion, is not shown in the drawings.

The lower portion of the bore 28 is of 30 smaller diameter, being enlarged at 34 to provide a seat for a valve 35, which has a stem 36 extending downwardly into the bore 22 nearly, but under normal conditions not quite to the top of the push-tube 24. The 35 upper and larger portion of the bore 28 is preferably again reduced in diameter by means of the removable plug 37, the top of which provides a seat for the valve 38 which has a stem 39 projecting downwardly and 40 extending nearly but under normal conditions not quite to the valve 35. The plug 31 which seals the top of the bore 28 preferably provides a chamber 40 in which may be mounted a spring 41 to facilitate the 45 firm seating and quick action of the valve 38. In a precisely similar manner the bore 29 is provided with a valve 42 which has a downwardly projecting stem 43 extending into the chamber 22 and preferably terminating—for reasons hereinafter explained—a slightly less distance from the top of the push-tube 24 than the distance between the end of the stem 36 and the top of said tube. Above the valve 42, the bore 29 is again reduced in diameter by means of the cylindrical plug 44 which provides a seat for the valve 45, the stem 46 of which projects downwardly with the end thereof slightly closer to the valve 42 than the end of the 55 stem 39 to the valve 35. The plug 32 is similarly of a construction to provide the small chamber 47 in which the spring 48 similarly presses against the valve 45. The valve bore 30 is of precisely similar configuration and correspondingly valved. The

chambers 40 and 47 are connected by means of a duct 49, and the corresponding chamber near the upper end of the duct 30 is open to said duct 49, and therefore to the chambers 40 and 47, by means of the duct 50.

From the valve bore 29, between the valves 45 and 42, leads the duct 51 which has a lateral extension 52 into and through the threaded plugs 53 to which is secured the coupling or connection at the end of the pipe 19, whereby said pipe is open through said duct to the valve bore 29 between said valves 45 and 42. Similarly, a duct 53 leads from the valve bore 28 between the valves 38 and 35, which duct has a lateral extension 54 extending into and through the plug 55 which is threaded for the reception of the coupling or connection 56 at the end of the pipe 18, whereby said pipe is open through said ducts to the valve bore 28 between the valves 38 and 35. In a precisely similar manner, a duct 57 (see Fig. 4) leads from the bore 30 between the two valves in said bore, to and through a lateral extension thereof in the plug 58, which is threaded for the reception of a suitable coupling or connection at the end of the pipe 17, whereby said pipe is open through said duct to the bore 30 between the two valves in said bore.

From the chamber 40 near the upper end 95 of the bore 28 and above the valve 38, a lateral duct 59 leads to and through the plug 60, which is threaded for the reception of a coupling or connection 61 at the end of the pipe 62 which, through a similar coupling 63 at the other end thereof and the duct 64 in the ram cylinder 65, leads to the pressure chamber 66 underneath the ram 67. Similarly, from the chamber 47 above the valve 45 in the bore 29, a lateral duct 68 leads to and through the threaded plug 69 to which is secured the coupling or connection 70 at the end of the pipe 71 which leads through the coupling 72 to the pressure chamber underneath the ram 73 in the ram cylinder 74. 110

At the lower end of the member 20 is provided a lateral bore to the lower end of the vertical bore 22, which is threaded for the reception of the screw plug 75 which closes and seals said bore. This plug 75 provides 115 bearings for the shaft 76, projecting into the bore 22 and having mounted on its interior end the cam 77 in co-operative positional relation to the lower end of the push-tube 24. This cam is of such form and so mounted 120 that under normal conditions it supports said push tube 24 against the action of the spring 26 with the upper end of said tube non-interferent with automatic action of any of the valves in the valve bores 28, 29 and 30. The shaft 76 is rotated to operate the cam 77 by means of a lever 78 which is suitably secured in the head 79 at the exterior end of said shaft. 125

A lateral duct 80 leads from the bore 22 130

to and through the nipple 81, by means of which a flexible pipe or tube 82 is connected to the member 20 and open at all times to the interior of the bore 22. The pipe 82 leads to the tank or barrel 83, or other convenient source of liquid supply, which is preferably located in an elevated position to facilitate the flow of liquid through the pipe 82 under the force of gravity.

5 It will be noted that all of the valves are downwardly seating and therefore are normally seated under equal liquid pressures. The upper valve in each of the bores 28, 29 and 30 is, however, positively seated under 10 action of its spring. It will therefore be apparent that when one of the pumps alone is operated, as, for example, the pump 13, the up-stroke of the piston in said pump will cause the formation of a partial vacuum in 15 the pump chamber and the flow of liquid, under the unequal pressures thus created, from the tank 83, or other source of supply, through the pipe 82, into the lower portion of the bore 29 and past the valve 42, which 20 it easily unseats, and thence through the duct 51 and the pipe 19 to the chamber underneath the piston in the pump 13. Upon the down stroke of said piston, the excess of 25 pressure above the valve 42, assisted by the force of gravity, will seat said valve and the liquid will be forced upwardly through the upper portion of the bore 29, past the valve 45, which it easily unseats, into the chamber 47 where it is divided between the ducts 30 leading to the two pipes 62 and 71, through which the liquid is directed into both ram chambers. The pressure valves at the top of the bores 28 and 30 remaining seated, it 35 will be apparent that the pump 13 (and the same is true of any one of said pumps) may 40 be alone operated for the purpose of the generation of increased power in view of reduced speed under the well-known principles of hydrostatics. Whether or not the pump 45 13 is operated—or both pumps 11 and 13—it will be similarly apparent that the up-stroke of the piston in the pump 12 will cause the flow of liquid from the source of supply through the pipe 82 into the bore 22, 50 thence past the valve 35 in the bore 28 and through the duct 55 and the pipe 18 to the chamber underneath the piston in said pump. Upon the down-stroke of this piston, the valve 35 will be seated under the 55 excess of pressure above the same, and the liquid from the pump 12 will be directed through the upper portion of the bore 28 past the valve 38 and into the chamber 40, where it is similarly divided between the two 60 rams or pressure chambers in the manner hereinbefore described. It will be similarly apparent that irrespective of operation of the pumps 12 and 13, up-stroke of the piston in the pump 11 will cause the flow of liquid 65 from the source of supply to the pump

chamber and that upon down-stroke of said piston the liquid will be forced in an identical manner to the chamber at the top of the valve bore 30, where it is similarly divided between the ram or pressure chambers. It 70 will therefore be seen that without in any-way manipulating the valves in the member 20, or otherwise necessitating any manual controlling operations, any one, any two, or all of said pumps may be operated and the 75 operations thereof be effective.

If speed is desired, and therefore the forcing of a large volume of the liquid into the pressure chambers, the three pumps may be operated until such time as it is desired to 80 sacrifice speed for increased power at which time ceasing the operation of one or more of said pumps will leave effective the operations of the remaining pumps or pump. Should these pumps be located in such positions, relative to the ram members of the device, that signaling is impossible or difficult, it will be seen that an operator stationed at the location of the valve controlling means may himself render one or more 85 of said pumps inoperative by turning the lever 78 through an arc sufficient to raise the push tube 24 until the end thereof has contacted with the lower end of the stem 43 and raised the valve 42 off its seat without, 90 however, interfering in any way with automatic action of any of the remaining valves. For this purpose I vary the lengths of the lower valve stems in the bores 28, 29 and 30, the valve 42 being first forced off its seat, 95 100 which renders the pump 13 alone inoperative—although the pumping operations are continued, the down-stroke of the piston in said pump forcing the liquid along the path of least resistance and therefore back into 105 the tank 83. By continuing rotation of said lever 78 through a slightly greater arc, another of the lower valves in said bores is similarly held off its seat, whereby two of 110 said pumps are rendered effectively inoperative. Further rotation of said lever 78 will next cause all three of the lower valves to be held off their seats, thus rendering operations of all the pumps ineffective without, 115 however, unseating any of the upper valves in said bores. Means for thus rendering one or more of said pumps effectively inoperative will be seen to be particularly desirable when three or more pumps are coupled or connected to a common source of power 120 and therefore can only be operated jointly.

As is well known, it is not infrequently desirable to have the pressure continuously generated and with substantial uniformity. This may be accomplished mechanically (see 125 Fig. 6) by connecting the pistons to suitable double cranks 84, 85 and 86, respectively, on a shaft 87 driving up a pulley 88 or other similar power transmitting means, these cranks being spaced apart by equal arcs 130

(120° each, where three pumps are employed) with respect to the circumference of the shaft 87. Of course, under such conditions, it is impossible to operate any less than all of the pumps, and therefore should it become desirable to reduce the number of effectively operating pumps to two or to one, this could only be done in the manner hereinbefore set forth through operation of the cam 77.

In addition to controlling the flow from each of the pumps, it will be apparent that the operator stationed at the location of the controlling means, may, when desired, simultaneously relieve the pressure in the ram chamber, or all ram chambers if more than one are employed. This he would do by turning the lever 78 through a still greater arc and thus causing the cam 77 to raise the push-tube 24 sufficiently to cause the lower valve having the longest stem—as for instance, the valve 42—to impinge against the longer stem of the corresponding upper valve—as for instance, the stem 46 of the valve 45—and first unseat the latter. It will be apparent that with so powerful a device as the one herein shown and described, great pressures may be generated within the ram chambers and, therefore, no little force is required to start the unseating of one of the pressure valves. Obviously, it would require twice the force to simultaneously unseat two of said valves and three times this force to simultaneously unseat all three thereof. By varying the lengths of the valve stems, as hereinbefore described, I first cause at least the partial unseating of one of said upper valves only. The instant that the valve is even to the slightest extent raised from its seat, the pressure is equalized on both sides thereof and its further unseating requires but little effort. Subsequently, another or all of said pressure valves may be raised to more rapidly withdraw the liquid from the ram or pressure chambers for the purposes of the removal or readjustment of the rams.

While I have shown and described an apparatus comprising three pumps and two rams it will be apparent that more than three pumps may be employed, and even more apparent that the joint pressure of all the pumps may be applied to a single ram or may be distributed through more than two thereof. For all practical purposes, however, I have found that three pumps constitute about the maximum number of pressure generators which can be satisfactorily joined for ordinary practical purposes, and that while the joint pressures may be at times rendered operable through a single ram, it is the more common practice with these more powerful generators to distribute the generated pressure between two of said applying devices. An apparatus of this character is more widely employed in exca-

vations which must extend under the foundations of buildings, and in providing both temporary and permanent supports and sub-foundations, it is not often practicable to locate a single jack or ram directly under the point at which the pressure must be applied, but the rams or jacks must be located one at each side of said point with suitable gripping, bracing, or other connecting means therebetween. Under such conditions it will be apparent that the pressures in the ram chambers must be equal and should be simultaneously relieved.

With the three pumps independently actuated, as shown in Fig. 1, they will be, as a rule, of different capacities, as hereinbefore suggested. Under these conditions, the largest pump would first be operated, in order to raise the ram or rams to the point of contact with the load, after which the workman would step to the second pump, operation of which would generate greater pressure at a sacrifice of speed, and when the ram or rams were raised to the point where they receive the full weight of the load, the workman would step to the smallest and therefore the most powerful pump which would alone be operated to do the required work.

Many modifications of minor details of my improved hydraulic pressure generating and applying apparatus will doubtless readily suggest themselves to those skilled in the art to which it appertains, and I therefore do not desire to limit my invention to the specific construction and arrangement herein shown and described.

I claim as new and desire to secure by Letters Patent:

1. In combination, a plurality of at least three separate pumps and means apart therefrom for applying the generated pressure, the pump and pressure valves seating downwardly in an individually moving fitting which is provided with means for the manual control of said valves.

2. In combination, a plurality of at least three separate pumps, means apart therefrom for applying the generated pressures, the pump and pressure valves seating downwardly in an individually movable fitting which is provided with means for the manual control of said valves, and means for insuring substantially vertical operation of said valves during use of the device.

3. In combination, a plurality of at least three separate pumps and means apart therefrom for applying the generated pressures, the pump valves seating downwardly in an individually movable fitting which is provided with means for successively unseating said valves to render one or more of said pumps inoperative.

4. In combination, a plurality of at least three separate pumps, means apart therefrom for applying the generated pressures,

the pump valves seating downwardly in an individually movable fitting which is provided with means for successively unseating said valves to render one or more of 5 said pumps inoperative, and means for insuring substantially vertical operation of said valves while the device is in use.

5. In combination, a plurality of at least three separate pumps and means apart therefrom for applying the generated pressures at a plurality of selective points, the pump and pressure valves seating downwardly in an individually movable fitting which is provided with means for equalizing the applied pressures and with means for the manual control of said valves.

6. In combination, a plurality of at least three pumps and means apart therefrom for applying the generated pressures, the pump and pressure valves seating downwardly in an individually movable fitting which is provided with means for the manual control of said valves to render one or more of said pumps inoperative, said means being further operable to relieve the pressure at the point of application.

7. In combination, a plurality of at least three separate pumps and means apart therefrom for applying the generated pressures, the pump valves seating downwardly in an individually movable fitting which is provided with means for equalizing the applied pressures and with means for the manual control of said valves to render one or more of said pumps inoperative, said last-mentioned means being further operable to relieve the pressure at the point of application.

8. In combination, a plurality of at least three separate pumps, means apart therefrom for applying the generated pressures, the pump and pressure valves seating downwardly in an individually movable fitting, said fitting being provided with means for equalizing the applied pressures and with means for successively unseating said valves to render one or more of said pumps inoperative and finally relieve the applied pressures, and means for insuring vertical operation of said valves during use of the device.

9. In combination, a plurality of at least three separate pumps and means apart therefrom for applying the generated pressures at a plurality of selective points, the pump valves seating downwardly in an individually movable fitting, said fitting being provided with valve-controlling means for successively rendering ineffective the operations of said pumps and for equalizing and finally relieving the applied pressures.

10. In combination, a plurality of at least three separate mechanisms for generating hydraulic pressures, separate means for applying the generated pressures, suitable con-

duits from each of said generating mechanisms and to said applying means, said conduits uniting in an individually movable fitting, a source of liquid supply and a conduit therefrom common to each of the conduits from said generating mechanisms, requisite pump and pressure valves in said conduits and in said fitting, and means for manually controlling said valves.

11. In combination, a plurality of at least three separate mechanisms for generating hydraulic pressures, separate means for applying the generated pressures, suitable conduits from each of said generating mechanisms and to said applying means, said conduits uniting in an individually movable fitting, a source of liquid supply and a conduit therefrom common to each of the conduits from said generating mechanisms, requisite pump and pressure valves in said conduits and in said fitting, and means common to all of said valves for the manual operation thereof.

12. In combination, a plurality of at least three separate mechanisms for generating hydraulic pressures, separate means for applying the generated pressures, suitable conduits from each of said generating mechanisms and to said applying means, said conduits uniting in an individually movable fitting, a source of liquid supply and a conduit therefrom common to each of the conduits from said generating mechanisms, a valve in each of said last-mentioned conduits and in said fitting checking back flow from a pump to said source of supply, valves checking back flow from said pressure-applying means, and means for first consecutively unseating said first-mentioned valves and subsequently consecutively unseating said last-mentioned valves, in order.

13. In combination, a plurality of at least three separate mechanisms for generating hydraulic pressures, separate means for applying the generated pressures, suitable conduits from each of said generating mechanisms and to said applying means, said conduits uniting in an individually movable fitting, a source of liquid supply and a conduit therefrom common to each of the conduits from said generating mechanisms, a valve in each of said last-mentioned conduits and in said fitting checking back-flow from a pump to said source of supply, valves checking back flow from said pressure applying means, and means common to all of said valves for first consecutively unseating the valves which check back-flow to the source of supply and subsequently consecutively unseating the valves which check back-flow from the pressure applying means.

14. In combination, a plurality of at least three separate mechanisms for generating hydraulic pressures, separate means for applying the generated pressures, suitable

conduits from each of said generating mechanisms and to said applying means, said conduits uniting in an individually movable fitting, a source of liquid supply and a conduit therefrom common to each of the conduits from said generating mechanism, requisite pump and pressure valves in said conduits and in said fitting, all of said valves seating downwardly, means for manually controlling said valves, and means for insuring substantially vertical operation of said valves during use of the device.

15. In combination, a plurality of at least three separate mechanisms for generating hydraulic pressures, separate means for applying the generated pressures, suitable conduits from each of said generating mechanisms and to said applying means, said conduits uniting in an individually movable fitting, a source of liquid supply and a conduit therefrom common to each of the conduits from said generating mechanisms, requisite pump and pressure valves in said conduits and in said fitting, all of said valves seating downwardly, means common to all of said valves for the manual control thereof, and means for insuring substantially vertical operation of said valves during use of the device.

16. In combination, a plurality of at least three separate mechanisms for generating hydraulic pressure, separate means for applying the generated pressures, suitable conduits from each of said generating mechanisms and to said applying means, said conduits uniting in an individually movable fitting, a source of liquid supply and a conduit therefrom common to each of the conduits from said generating mechanisms, a

valve in each of said last-mentioned conduits and in said fitting checking back-flow from the pump to said source of supply, valves in said fitting checking back-flow from all of said pressure applying means, 45 said valves seating downwardly, means for first consecutively unseating said first-mentioned valves and subsequently consecutively unseating last-mentioned valves, in order, and means for insuring substantially vertical operation of said valves during use of the device. 50

17. In combination, a plurality of at least three separate mechanisms for generating hydraulic pressures, separate means for applying the generated pressures, suitable conduits from each of said generating mechanisms and to said applying means, said conduits uniting in an individually movable fitting, a source of liquid supply 60 and a conduit therefrom common to each of the conduits from said generating mechanisms, a valve in each of said last-mentioned conduits and in said fitting checking back flow from a pump to the source of supply, a 65 check valve in each of said passages to said pressure applying means, all of said valves seating downwardly, means common to all of said valves for first consecutively unseating the valves checking back flow of the 70 source of supply and subsequently consecutively unseating the valves which check back flow from the pressure applying means, and means for insuring substantially vertically operation of said valves during 75 use of the device.
